UNITED STATES PATENT OFFICE.

ALBERT ANDERSEN, OF CHICAGO, ILLINOIS, ASSIGNOR TO AUTOMATIC ELECTRIC COMPANY, OF CHICAGO, ILLINOIS, A CORPORATION OF ILLINOIS.

MEASURED-SERVICE TELEPHONE SYSTEM.

Application filed December 30, 1913. Serial No. 809,542.

To all whom it may concern:

Be it known that I, ALBERT ANDERSEN, a citizen of the United States of America, and resident of Chicago, Cook County, Illinois, have invented certain new and useful Improvements in Measured-Service Telephone Systems, of which the following is a specification.

My invention relates to measured service 10 telephone systems, and more particularly to systems in which the connection is established between two lines by automatic switches.

The object of my invention is to provide 15 a measured service device which is controlled by a time mechanism whereby it will be operated at predetermined intervals of time. Heretofore, in systems where a measured service device is provided at the substation, this device has usually been operated 20 upon the response of the called subscriber, but no means were provided to require further operation of the measured service device should a connection remain established 25 more than a predetermined period of time.

The object of my invention is to provide means for preventing such connection remaining established more than a predetermined period of time without again operating 30 the meter.

By my invention I provide a time mechanism at the central office which is started in operation when the called subscriber responds, which time mechanism, at the end of 35 a predetermined period, renders the talking circuit inoperative until the calling subscriber again operates his measured service device.

A further feature of my invention is the 40 provision of a signal for notifying the calling subscriber that it is nearly time to again operate his measured service device. If this device is a coin controlled register, this signal gives the subscriber sufficient time to 45 have a coin ready to deposit in the coin-collecting device as soon as the time-controlled mechanism renders the talking circuit inoperative.

These and other objects of my invention 50 will be more readily understood by reference to the accompanying drawings, in which I have illustrated one specific embodiment of my invention in connection with an automatic telephone system of a well-known 55 type.

In the drawing I have shown a complete circuit connection between a calling substation A and a called substation A'.

The automatic system represented herein comprises the subscriber's substation A together with the individual switch C at the central office, a master switch D, a connector H, the called subscriber's line switch C' and the called substation A'. It will be clearly understood by those versed in the art that so-called selector switches may be inserted 60 in the system, thereby increasing the capacity of the exchange without departing from the principle of my invention. The so-called selector switches may be of a type 65 similar to those disclosed in British patent to T. G. Martin No. 1419 of 1910.

The subscriber's substation A is of any suitable or approved type and, as shown, comprises the usual receiver 25, switch-hook 70 26, transmitter 27, induction coil 28, ringer 29 and condenser 30. Being an automatic substation it is also provided with an impulse transmitter or calling device which is represented herein by a pair of impulse 80 springs 31 and 32 and an impulse wheel 33. The impulse wheel 33 carries upon its periphery impulse teeth 34 and is secured to a shaft 35, to which latter is also attached a dial (not shown) provided with finger holes, 85 through the medium of which the impulse wheel may be rotated. As the impulse wheel is returned to normal position by a spring (not shown) after it has been rotated for any digit, each of the teeth 34 which passes 90 the end of the spring 31 forces said spring out of engagement with the spring 32. The number of times these springs are separated depends upon the digit called.

The coin-collecting device L associated 95 with the substation A is of the same general type as disclosed in British patent to Walter Howley Derriman No. 687 of 1912. The coin-collecting device, as herein represented, consists essentially of a polarized electromagnet, the coils 9 and 10 of which are connected in series with the substation A. The springs 4, 5 and 6 are so arranged that when their contacts are closed, the transmitter 37 is short-circuited and the receiver 25 is 105 shunted by the resistance coil 11. The lower end of the spring 4 carries a swinging arm 7 to which is attached a small lug 13. If the polarized magnet is energized in one direction, the lower end of the arm 12, which is 110

attached to the armature 3, will be tilted to the right and is carried behind the small lug 13. If the magnet then be energized in the opposite direction, the arm 12 engages 5 the lug 13 and carries the arm 7 over with it, thus causing the springs 4, 5 and 6 to be brought into engagement.

The subscriber's switch C is of the general type of subscriber's switch shown in 10 British patent to R. W. James No. 26,301 of 1906, being, however, of the particular type disclosed in said British Patent No. 1419 of 1910. This line switch comprises, among other details, a plunger (not shown) attached to the end of a so-called plunger arm 39, which is controlled by the magnet 40. The magnet 40 comprises four windings, namely, a pull-down winding 43, a cut-off or holding winding 44, a line winding 46 15 and an auxiliary winding 45. The core of the magnet 40 is so constructed that the magnetic circuit of the windings 43 and 44 is separate from that of the windings 45 and 46. The winding 43 operates both the plunger arm 39 and the cut-off armature 41, while the winding 44 is only strong enough 20 to operate the cut-off armature 41 and to hold the plunger arm 39 in its operated position. When the plunger arm 39 is operated, 25 the plunger is forced into a bank of contact springs, forcing the springs 49, 51, 53 and 55 into engagement with the springs 50, 52, 54 and 56, respectively. Although only one set of springs (49 to 56) is shown, each 30 line switch is provided with a plurality of such sets, each set forming the terminal of a trunk line leading to a connector switch H. Each trunk line is connected in multiple with the corresponding springs of all the 35 line switches of the group which is controlled by the master switch D. The individual switch C is controlled by the subscriber through the medium of the line relay 46, as will be hereinafter more fully explained.

The master switch D is of the same general type as that disclosed in the above-mentioned British Patent No. 26,301 of 1906, being, however, of the particular type disclosed 50 in said British Patent No. 1419 of 1910. The function of the master switch, as is well known, is to maintain the plungers of all the idle line switches in position to engage the terminal of an idle trunk line.

The connector switch H is of the same general type of connector switch disclosed in United States Letters Patent No. 815,176, granted March 13, 1906, to Keith, Erickson and Erickson, the circuits, however, being 55 modified to adapt the switch to operate in a system in which the central office apparatus is controlled by impulses delivered over the two sides of the line in series. The connector is provided with a shaft (not shown) carrying the wipers 14, 15 and 16

which is controlled by the vertical magnet 17 and the rotary magnet 18. The usual side switch comprising the wipers 19, 20, 21 and 22 is controlled by the private magnet 23 in the usual well-known manner. The 70 magnet 24 is the usual release magnet. The line relay 36 is connected with the calling line through the reversing springs of the so-called back-bridge relay 37. The said back-bridge relay is the means by which 75 talking current is supplied to the called line. The ringing relay 38 is the means through which ringing current is applied to the called line.

The time-controlling device K associated 80 with the connector H is controlled through the medium of a relay 67, which is connected in series with the windings of the back-bridge relay 37 and is operated when the called subscriber answers. This time-controlling device K, as herein represented, consists of a ratchet wheel 68, to which is attached a lever arm 69, and a motor magnet 70 which is controlled by a master clock M. The lever 69 is arranged to open the circuit 90 of the controlling relay 67 after the said motor magnet has stepped the ratchet wheel 68 around a certain predetermined number of steps. The relay 67, upon energizing, closes the circuit of the motor magnet 70 at 95 the springs 94 and also permits the holding pawl 93 to drop into engagement with the ratchet 68. The relay 67, upon deenergizing, allows the ratchet wheel to be restored to normal by means of a retractile spring (not 100 shown), and also allows the springs 71 to again close the circuit of said controlling magnet 67.

The called subscriber's line switch C', substation A' and coin-controlling device 105 L' are similar in all respects to the line switch C, substation A and coin-controlling device L.

Having given a general description of the apparatus, in order to give a complete understanding of my invention I will now describe how the subscriber at substation A may establish connection with the subscriber at substation A'. We will assume that the number of the called substation is 115 20. When the calling subscriber removes his receiver preparatory to making a call, the switch-hook rises, permitting the spring 95 to pass out of engagement with the spring 97 and into contact with the spring 96, 120 whereby the circuit of the ringer 29 and the condenser 30 is broken, and a bridge consisting of the substation transmitter, primary winding of the induction coil and the windings of the coin-collecting device is 125 closed across the line conductors 98 and 99. The closure of this bridge across the line completes an energizing circuit through the line winding 46 of the switch C, thereby attracting the line armature 42. At this time 130

the current through the coin-collecting device L is in the direction to attract the armature 3 to the coil 10, thereby carrying the arm 12 behind the lug 13. The armature 5 of the line switch C, upon being attracted, closes a circuit through the pull-down winding 43 in series with the auxiliary winding 45. The pull-down coil, upon energizing, attracts the plunger arm 39 to force 10 the plunger into the bank of contacts 49 to 56, inclusive. It also operates the cut-off armature 41, whereby the springs 101 and 104 are carried out of engagement with the springs 102 and 103, respectively, thus disconnecting the line winding 46 from the line. The armature 42 does not fall back immediately, however, owing to the fact 15 that the winding 45 is still in series with the pull-down winding 43. Upon the plunger 20 arm 39 being attracted, the springs 108 and 109 are brought together to short-circuit the auxiliary winding 45, making same slightly slow acting. The armature 42, being slow to fall back, allows sufficient time for a 25 holding circuit to be closed in the switch ahead for the cut-off or holding winding 44. The engagement of the springs 49 and 55 with the springs 50 and 56, respectively, extends the subscriber's line to the line relay 30 36 of the connector H. The line relay 36 of the connector H is thereupon energized, closing a circuit through the slow acting relay 74. The relay 74, upon energizing, closes the above-mentioned holding circuits 35 through the cut-off winding 44 of the line switch C. This circuit extends from ground G² through the contact of springs 75, bank springs 52 and 51 and the cut-off winding 44 to battery B, thence through 40 battery B to ground G. The winding 44, upon energizing, holds the armature 41 and the plunger arm 39 in their operated positions after the circuit of the pull-down winding is broken by the falling back of the 45 line armature 42. A guarding ground potential is supplied to the connector private bank contacts of the calling line as soon as the relay 74 is energized. This potential extends over the circuit just traced to the 50 bank spring 51, thence over the trunk 115 to said private bank contact. The energization of the relay 74 also prepares a circuit for the vertical magnet 17 by bringing into engagement the springs 76 and 77 and opens 55 the circuit of the release magnet, at the springs 77 and 78.

The calling subscriber now operates his dial for the first digit 2 of the called number, whereby the substation impulse springs 60 31 and 32 are operated twice momentarily, each time breaking the circuit of the connector line relay 36. Since the relay 74 is slow acting it does not deenergize during the momentary interruptions of its circuit 65 by the relay 36, so that each time the latter relay is deenergized, a circuit is closed extending from ground G³ through the contact of springs 80 and 79, springs 77 and 76, relay 82, vertical magnet 17 and the side switch wiper 19 (in first position) to battery B. The vertical magnet 17 receives two impulses over this circuit and operates to raise the switch wipers 14, 15 and 16 to a position opposite the second level of bank contacts. The relay 82, which is included in 70 series with the vertical magnet, remains energized during the entire time that impulses are being transmitted through it and operates to close the circuit of the private magnet 23. This circuit extends from ground G³ through the contact of springs 85 and 83 and the magnet 23 to battery B. After the last impulse is delivered, the relay 82 opens the circuit of the private magnet 23, which, upon deenergizing, permits the side switch 75 wiper 19 to advance from first to second position. The movement of the side switch wiper 19 from first to second position transfers the battery connection from the vertical magnet 17 to the rotary magnet 18. The calling subscriber now operates his calling device for the last digit 0, in response to which the connector line relay operates to transmit ten impulses through the rotary magnet 18 in series with the relay 82, whereby the 80 shaft wipers are rotated onto the contacts of the desired line. The said circuit extends from ground G³ through the contact of springs 80 and 79, springs 77 and 76, relay 82, springs 86, rotary magnet 18 and the side switch wiper 19 (in second position) to battery B. The relay 82 operates in response to the impulses for this digit in the same manner as for the previous digit to cause the private magnet 23 to advance the 85 side switch one more position, i. e., from second to third position. By the engagement of the side switch wipers 21 and 22 with their third-position contact points, and by the energization of the bridge-cut-off winding 87 of the switch C', the connection 90 is completed with the called substation. The circuit for the bridge-cut-off winding extends from ground G⁷ through the side switch wiper 20 (in third position), private wiper 15, conductor 88 and the cut-off winding 87 to battery B. A guarding ground potential is supplied to the connector private bank contact 89 over the above-traced 95 circuit which prevents the called line from being seized by some other connector switch. By the engagement of the side switch wiper 19 with its third-position contact point, the circuit of the ringer relay 38 is closed. This circuit extends from ground G⁸ through the 100 interrupter 90, relay 38, contact of springs 91 and the side switch wiper 19 (in third position) to battery B. The ringer relay disconnects the calling line from the called 105 line and bridges the ringing current gen- 110

115

120

125

130

erator R across the called line to signal the called subscriber. The ringer relay is energized intermittently through the medium of the interrupter 90.

5 Upon the response of the called subscriber his line is provided with talking current through the windings of the back-bridge relay 37 and the controlling relay 67 in series. The relay 37, upon energizing, closes a circuit for the ringer cut-off relay extending from ground G⁷ through the side switch wiper 20 (in third position), contact of springs 114 and 113 and the said ringer cut-off relay 91^a to battery B. The ringer cut-off relay 91^a, upon energizing, interrupts the circuit of the ringer relay 38 at the springs 91 and closes a locking circuit for itself through the springs 92 independent of the springs 113 and 114. The energization of 10 the back-bridge relay 37, upon the response of the called subscriber, reverses the battery connections of the line relay 36 with regard to battery B, whereby the direction of the current in the calling line is reversed. The 15 reversing of the current in the calling line causes the polarized relay of the coin-collecting device at the substation A to attract its armature in the opposite direction—that is, toward the coil 9. When the armature is 20 attracted in this direction, it carries the arm 7 to the left, forcing the springs 4, 5 and 6 into engagement. The engagement of said springs, as hereinbefore stated, short-circuits the transmitter 27 and shunts the secondary winding of the induction coil 28 with the resistance 11. The short-circuiting of 25 the transmitter makes it impossible for the calling subscriber to talk to the called subscriber through the transmitter. The shunting of the receiver does not prevent the calling subscriber from hearing the called subscriber answer, but is sufficient to prevent him from talking through his receiver. When the calling subscriber hears the called 30 subscriber answer, he deposits his coin in the coin chute (not shown) of the coin-collecting device L, thus causing the arm 7 to be released from the arm 12, thereby allowing the springs 4, 5 and 6 to return to normal and the apparatus rendered operative 35 for talking purposes. Upon the energization of the controlling relay 67 of the time-controlling device K, the circuit of the motor magnet 70 is closed at the springs 94 and 40 this motor magnet is thus intermittently operated by means of the clock mechanism M. At the same time the operation of this relay 67 permits the holding pawl 93 to drop into engagement with the ratchet 68. As 45 this arm 69 is rotated, it first closes the springs 100, which causes a signal to be transmitted to the calling subscriber. The path of this signaling current is as follows: from the conductor 101 through the springs 50 100, over the calling line conductors 98 and

99 and through the substation A, thence back through battery B. As the arm 69 continues to rotate, it opens the springs 71, thus opening the circuit of the back-bridge relay 37 and the controlling relay 67. The 55 relay 37, upon deenergizing, causes the battery to be reversed back to normal on the calling line, causing the arm 12 to be again carried back of the lug 13. The relay 67, upon deenergizing, allows the time-controlling device K to be restored to normal, thus again closing the circuit of the back-bridge relay 37 and the controlling relay 67. The 60 said back-bridge relay 37, upon energizing, again reverses the current in the calling line, 65 thus rendering the talking circuit inoperative, the same as stated above, and the calling subscriber must again deposit another coin before the conversation can again be resumed. The above result occurs at predetermined intervals of time, thus making it necessary for the calling subscriber to deposit coins at regular intervals of time.

The purpose of the signal operated by the springs 100 is to advise the calling subscriber 90 that if he wishes to continue conversation he must soon again deposit another coin in the coin-collecting device and thus give him an opportunity to have his coin ready to deposit as soon as the talking circuit is again 95 rendered inoperative by the separation of the springs 71.

After the conversation is completed, the connection is released by the hanging up of the receiver at the calling substation in the 100 usual and well-known manner.

From the foregoing it will be seen that the calling subscriber's telephone set is rendered inoperative when the called subscriber answers. The calling subscriber can listen 105 and hear the response of the called subscriber, but cannot use his transmitter until he has deposited a coin. Furthermore, it will be seen that I have devised a very efficient means for placing a time limit upon 110 the length of time that a conversation may be carried on without depositing an extra coin. I obtain the above result by rendering the calling subscriber's substation inoperative for talking purposes after predetermined intervals of time, thus making it 115 necessary to deposit an extra coin before the conversation may be further continued.

While I have illustrated my invention in connection with one particular type of automatic system, it will, of course, be understood that it is capable of use with many other forms of systems, and is equally as well adapted for use in connection with semi-automatic systems, i. e., systems in which a 120 manual link circuit is employed in combination with automatic means for establishing a connection between two subscribers' lines.

What I claim as my invention is:

1. In a telephone system, a plurality of 125

- subscribers' lines, means including automatic selecting and connecting switches for establishing a talking circuit between two of said lines, means controlled by the response of 5 the called subscriber for reversing the current in the calling line, means controlled by said reversal of current for rendering said talking circuit inoperative, a measured service device for again rendering said talking 10 circuit operative, a time-controlled mechanism, means controlled by the response of the called subscriber for starting said mechanism in operation, means controlled by said mechanism for momentarily reversing the 15 current in the calling line at predetermined intervals of time to again render said talking circuit inoperative, and means controlled by subsequent operations of said measured service device for again rendering said talking 20 circuit operative.
2. In a telephone system, a plurality of subscribers' lines, means including automatic selecting and connecting switches for establishing a talking circuit between two of said 25 lines, means controlled by the response of the called subscriber for reversing the current in the calling line, means controlled by said reversal of current for rendering said talking circuit inoperative, a coin-collecting 30 device, means controlled by the depositing of a coin in said device for again rendering said talking circuit operative, a time-controlled mechanism, means controlled by the response of the called subscriber for starting 35 said mechanism in operation, means controlled by said mechanism for momentarily reversing the current in the calling line at predetermined intervals of time to again render said talking circuit inoperative, and 40 means controlled by the depositing of subsequent coins in said coin-collecting device for rendering said circuit operative.
3. In a telephone system, a plurality of subscribers' lines, means for establishing a 45 talking circuit between two of said lines, a time-controlled mechanism, means controlled by the response of the called subscriber for starting said mechanism in operation, means controlled by said mechanism for rendering 50 said talking circuit inoperative at predetermined intervals of time and for giving the calling subscriber a signal before the talking circuit is rendered inoperative, and a measured service device on the calling line for again rendering said circuit operative.
4. In a telephone system, a plurality of subscribers' lines, means for establishing a talking circuit between two of said lines, a time-controlled mechanism, means controlled 55 by the response of the called subscriber for starting said mechanism in operation, means controlled by said mechanism for rendering said talking circuit inoperative at predetermined intervals of time and for giving the calling subscriber a signal before the talking circuit is rendered inoperative, a coin-collecting device, and means controlled by the depositing of a coin in said device for again rendering said talking circuit operative.
5. In a telephone system, a plurality of subscribers' lines, means including automatic selecting and connecting switches for establishing a talking circuit between two of said lines, a time-controlled mechanism, 70 means controlled by the response of the called subscriber for starting said mechanism in operation, means controlled by said mechanism for rendering said talking circuit inoperative at predetermined intervals of time and for giving the calling subscriber a signal before the talking circuit is rendered inoperative, a coin-collecting device, and means controlled by the depositing of a coin in said device for again rendering said talking circuit operative.
6. In a telephone system, a plurality of subscribers' lines, means for establishing a talking circuit between two of said lines, a time-controlled mechanism, means controlled by the response of the called subscriber for starting said mechanism in operation, means controlled by said mechanism for rendering said talking circuit inoperative at predetermined intervals of time and for giving the calling subscriber a signal over said line before the talking circuit is rendered inoperative, and a measured service device on the calling line for again rendering said circuit operative.
7. In a telephone system, a plurality of subscribers' lines, means for establishing a talking circuit between two of said lines, a time-controlled mechanism, means controlled by the response of the called subscriber for starting said mechanism in operation, electromagnetic means controlled by said mechanism for rendering said talking circuit inoperative at predetermined intervals of time and for giving the calling subscriber a signal before the talking circuit is rendered inoperative, and a measured service device on the calling line for again rendering said circuit operative.
8. In a telephone system, a plurality of subscribers' lines, means for establishing a talking circuit between two of said lines, a time-controlled mechanism, means controlled by the response of the called subscriber for starting said mechanism in operation, means controlled by said mechanism for rendering said talking circuit inoperative at predetermined intervals of time and for giving the calling subscriber a signal over said line before the talking circuit is rendered inoperative, a coin-collecting device, and means controlled by the depositing of a coin in said device for again rendering said talking circuit operative.
9. In a telephone system, a plurality of

subscribers' lines, means for establishing a talking circuit between two of said lines, a time-controlled mechanism, means controlled by the response of the called subscriber for starting said mechanism in operation, electromagnetic means controlled by said mechanism for rendering said talking circuit inoperative at predetermined intervals of time and for giving the calling subscriber a signal before the talking circuit is rendered inoperative, a coin-collecting device, and means controlled by the depositing of a coin in said device for again rendering said talking circuit operative.

15 10. In a telephone system, a plurality of subscribers' lines, means including automatic selecting and connecting switches for establishing a talking circuit between two of said lines, a time-controlled mechanism, means
20 controlled by the response of the called subscriber for starting said mechanism in operation, means controlled by said mechanism for rendering said talking circuit inoperative at predetermined intervals of time
25 and for giving the calling subscriber a signal over said line before the talking circuit is rendered inoperative, a coin-collecting device, and means controlled by the depositing of a coin in said device for again rendering
30 said talking circuit inoperative.

11. In a telephone system, a plurality of subscribers' lines, means including automatic selecting and connecting switches for establishing a talking circuit between two of said lines, a time-controlled mechanism, means controlled by the response of the called subscriber for starting said mechanism in operation, electromagnetic means controlled by said mechanism for rendering said talking circuit inoperative at predetermined intervals of time and for giving the calling subscriber a signal before the talking circuit is rendered inoperative, a coin-collecting device, and means controlled by the depositing of a coin in said device for again rendering said talking circuit operative.

12. In a telephone system, a calling and a called line, means including an automatic progressively movable switch for connecting said lines, means for assessing a charge to the calling subscriber at the beginning of the conversation, means for repeating the charge at intervals thereafter, and an audible signal to notify the calling subscriber each time an additional charge is assessed.

13. In a telephone system, a calling and a called line, means including an automatic progressively movable switch for connecting said lines, means for collecting a coin from 60 the calling subscriber at the beginning of the conversation, automatic means for requiring the collection of additional coins at intervals thereafter, and an audible signal to notify the calling subscriber each time 65 an additional coin is required.

14. In a telephone system, a calling and a called line, means including an automatic progressively movable switch for connecting said lines, automatic means for requiring the calling subscriber to pay before beginning conversation, automatic means for requiring another payment if the conversation extends beyond a predetermined time limit, and means for notifying the calling subscriber when the additional payment is required. 70 75

15. In a telephone system, a calling and a called line, means including an automatic progressively movable switch for connecting said lines, automatic means for requiring the calling subscriber to pay before beginning conversation, automatic means for requiring another payment if the conversation extends beyond a predetermined time limit, and an audible signal to warn the calling subscriber that the predetermined time has elapsed. 80 85

16. In a telephone system, a calling and a called line, means including an automatic progressively movable switch for connecting said lines, a coin collecting device for the calling subscriber, means for requiring the calling subscriber to deposit a coin in said device before beginning conversation, an automatic time controlled mechanism for interrupting the conversation at regular intervals thereafter to require the deposit of additional coins, and means for warning the calling subscriber before the conversation is interrupted. 90 95 100

17. In a telephone system, a calling and a called line, means including an automatic progressively movable switch for connecting said lines, means for collecting a coin from the calling subscriber before the talking circuit can be established, automatic means for disabling the talking circuit after a predetermined time to require the collection of another coin, a device for producing an audible distinctive tone, and means for connecting said device with the calling line to notify the calling subscriber that an additional coin is required. 105 110

18. In a telephone system, a calling and a called line, means including an automatic progressively movable switch for connecting said lines, a coin collecting device for the calling subscriber, means for requiring the calling subscriber to deposit a coin in said device before beginning conversation, an automatic mechanism for interrupting the conversation after a predetermined time to require the deposit of an additional coin, a device for producing an audible distinctive tone, and means for connecting said device with the calling line to notify the calling subscriber that an additional coin is required. 115 120 125

19. In a telephone system, a. calling and a called line, means for connecting said 130

vice for rendering the calling telephone inoperative for talking purposes, means comprising a coin collecting device for restoring the calling telephone to operative 5 condition, a battery for supplying talking current, means for reversing the current flow in the calling line to require the deposit of a coin before conversation can begin, means for momentarily reversing the 10 current flow in the calling line again after a predetermined time to require the deposit of another coin, and means for notifying the calling subscriber when an additional coin is to be deposited.

15 28. In a telephone system, a calling and a called line, means including an automatic progressively movable switch for connecting said lines, mechanism for rendering the telephone on the calling line inoperative for 20 talking purposes, a coin collecting device, means controlled by the deposit of a coin therein for restoring the calling telephone to operative condition, means for operating said mechanism to require the deposit of a 25 coin before conversation can begin, means for reoperating said mechanism after a predetermined time to require the deposit of an additional coin, a device for producing an audible tone, and means for connecting 30 said device with the calling line whenever an additional coin is required to notify the calling subscriber.

29. In a telephone system, a calling and a called line, automatic switches controlled 35 over the two sides of the calling line in series for connecting said lines, a talking transmitter at the calling station, a relay at the calling station connected in the line in series with said transmitter, means at the 40 exchange for operating said relay over the line to render the calling station inoperative for talking purposes, a measured service device operable by the calling subscriber to render the calling station operative, and a 45 device at the exchange operating periodically to reoperate said relay over the line circuit in order to require the calling subscriber to reoperate said measured service device.

30. In a telephone system, a calling and a 50 called line, means including an automatic progressively movable switch for connecting said lines, a closed control circuit for said switch including the two conductors of the calling line and a battery at the exchange 55 connected in series, means for reversing the connections of the line conductors with respect to the battery after the connection is established, means responsive to such reversal for requiring the calling subscriber to 60 pay before beginning conversation, and automatic means for requiring an additional payment at the end of a predetermined time interval thereafter.

31. In a telephone system, a calling and a 65 called line, means including an automatic

progressively movable switch for connecting said lines, a closed control circuit for said switch including the two conductors of the calling line and a battery at the exchange connected in series, means for reversing the 70 connections of the line conductors with respect to the battery after the connection is established, means responsive to such reversal for assessing a charge against the calling subscriber at the beginning of the conversation, and automatic means for assessing an additional charge at the end of a predetermined time interval thereafter. 75

32. In a telephone system, a plurality of subscribers' lines, means including automatic 80 selecting and connecting switches for establishing a talking circuit between two of said lines, means controlled by the response of the called subscriber for reversing the current in both conductors of the calling line, a polar relay responsive to said reversal of current for rendering said talking circuit inoperative, a coin collecting device, means controlled by the depositing of a coin in said device for again rendering said talking circuit operative, time controlled means for thereafter rendering said talking circuit inoperative at predetermined time intervals, and means controlled by the depositing of subsequent coins in said coin collecting 90 device for rendering said talking circuit operative. 95

33. In a telephone system, a calling and a called line, means including a subscriber controlled progressively movable switch for 100 connecting said lines, a closed control circuit for said switch including the two conductors of the calling line and a battery at the exchange connected in series, a talking transmitter at the station on the calling line supplied with current from said battery over said conductors, reversing mechanism in the battery feed connections at the exchange, a timing device for operating said mechanism periodically during conversation, and means 105 responsive to reversals of current in the calling line to assess charges against the calling subscriber. 110

34. In a telephone system, a calling and a called line, means including a subscriber controlled progressively movable switch for connecting said lines, a closed control circuit for said switch including a talking transmitter at the station on the calling line, a line relay in said switch, and the two conductors 115 of the calling line in series, a battery included in said circuit, mechanism for reversing the direction of current flow from said battery in said circuit, a timing device for operating said mechanism periodically 120 during conversation, and a measured service device including a magnet in the said control circuit sensitive to current reversals for assessing charges against the calling subscriber. 125

35. In a telephone system, a calling and a 130

called line, an automatic progressively movable switch, a line relay in said switch, a closed control circuit for said relay including a battery at the exchange and the two sides of the calling line in series, means at the station on the calling line for producing series of interruptions in said circuit to operate said line relay, whereby the said switch is actuated to effect connection between said lines, mechanism at the exchange for altering the connections between the conductors of the calling line and said battery to produce current changes in the line, a timing device for operating said mechanism periodically after the called subscriber answers, and a 15 measured service device having a magnet included in said control circuit during conversation and sensitive to said current changes to assess charges against the calling subscriber. 20

Signed by me at Chicago, Cook County, Illinois, this 22nd day of December, 1913.

ALBERT ANDERSEN.
